UNITED STATES PATENT OFFICE.

NATHAN C. MERRILL, OF VANCOUVER, BRITISH COLUMBIA, CANADA.

TILTABLE BED.

No. 880,682.

Specification of Letters Patent.

Patented March 3, 1908.

Application filed April 27, 1907. Serial No. 370,706.

To all whom it may concern:

Be it known that I, NATHAN C. MERRILL, citizen of the United States of America, residing at Vancouver, in the Province of British Columbia, Canada, have invented a new and useful Improvement in Tilttable Beds, of which the following is a specification.

This invention relates to an improvement in folding or tilting beds and is particularly directed to a means for counterbalancing the weight of the bed so as to render the operation of uptilting or pulling down more easy.

It also comprises certain subsidiary features whereby the construction of the bed is simplified and rendered more efficient.

The invention is particularly described in the following specification and illustrated in the drawings by which it is accompanied, in which:

Figure 1 is a side elevation of the bed and the bracket by which it is attached to a wall or panel showing the bed in the "down" or "in use" position and indicating by dot and dash lines the position of the head of the bed when uptilted, and Fig. 2 is a plan of the same.

In the drawings 2 represents the wall or panel to which the bed is attached, 3 being the brackets by which it is secured thereto.

The frame of the bed is represented by 4 and the swinging legs which support the foot of the bed when down for use, by 5.

The head of the bed frame 4 is supported by trunnions 6 in bearings in the brackets 3 which trunnions 6 are secured to or form an integral part of a light metal head plate 7 designed to prevent the pillows or bed clothes from being caught in the brackets 3 during movement. These head plates 7 are flanged

at 8 to support the head board 9, and at 10 to engage the underside of the bed frame 4, to which parts they may be secured by screws.

By this construction the position of the trunnion pin 6 is positively located from the head 45 and from the underside of the bed frame and the several parts are secured in a satisfactory manner. In a similar manner the mounting of each swinging leg 5 forms an integral part of a corner plate 11 secured to the foot of the

bed, which plate is provided with flanges 12 and 13 to engage respectively the foot board and side board of the bed frame.

Although described first, the foregoing are the subsidiary features referred to in the preamble of this specification. The essen-

tial feature of it lies in the manner hereinafter described by which the springs are applied to counterbalance the weight of the bed to facilitate the operation of raising and lowering it.

Along each lower side of the bed frame within a suitable casing and attached to the frame toward the foot of the bed at 15 are coil springs 16, to the free end of each of which is attached a wire rope or other flexible connection 17, which passes through the head board 9 between two grooves sheaves 18 and passing downward is anchored at a projection 20 from the lower edge of the bracket 3.

The position where the flexible connection 17 is anchored to the bracket 3 is located nearer to the face of the wall 2 than the fulcrum pin 6 on which the bed turns when being tilted, so that when the bed is tilted the position of least tension on the springs 16 is reached before the vertical position of the bed is attained and the bed requires to be pushed up to the vertical and to be latched there to remain in that position. The object 80 of this is that when the bed is in the vertical position it will have an initial tendency to fall outward from the wall when unlatched and bring it more conveniently within reach of the person lowering it.

The anchoring of the flexible connection 17 may be accomplished in any convenient manner, but I prefer to pass the end of the wire rope 17 through an aperture in the projection 20 and thereafter to secure it to the bracket 3 by a clip so that the adjustment of the tension of the springs 16 may conveniently be regulated to suit the weight of the bed and bedding.

The advantages which I claim for the features of construction revealed in the foregoing description are that the manufacture of the bed is simplified and that with its brackets it is entirely self-contained requiring no attachment of springs etc. to the wall or panel to which it is attached, and the weight of the bed may be so counterbalanced that a very slight effort is necessary to uptilt it and when required for use as soon as it is unlatched it will drop easily toward the downward position into the hands of the person lowering it being checked in such downward movement by the increasing resistance of the springs.

Having now particularly described my in-

vention and the manner of its use I hereby declare that what I claim as new and desire to be protected in by Letters Patent, is:

1. In a tiltable bed, a wall or panel, brackets projecting therefrom, a bed frame pivotally mounted on said brackets, means for counter-balancing said bed frame, said means comprising springs secured to the bed frame, flexible connections from the springs through the head of the bed, and secured to the supporting bracket whereby when the bed is in an up-ended position tension on the flexible connections will tend to move the bed toward its horizontal position, substantially as shown and described.

2. In a tiltable bed, the combination with a bed frame, brackets secured to a wall or panel in which the bed frame is pivotally mounted, springs secured in the bed frame, a pair of adjacent anti-friction rollers carried in the head of the frame, flexible connections from the springs through the head of the bed between the anti-friction rollers and secured to the brackets at their lower part, at a point nearer the wall than the anti-friction rollers when the bed is in an up-ended position, substantially as shown and for the purposes described.

3. In a tiltable bed, brackets projecting from a wall or panel, said bed including a bed frame pivotally mounted in said brackets, means for counter-balancing said bed, said means, comprising springs extending lengthwise within the bed frame and secured to the end of the bed frame further from the pivotal support, a flexible connection from the free end of the spring through the head of the bed and secured to the bracket adjacent to the position of the head of the bed frame when the same is in an up-ended position against the wall, but at a distance from the wall less than the distance from the wall to the pivotal axis of the bed, and means at the head of the bed for coöperating with said flexible connections to engage the same at a point further from the wall than the point at which the flexible connection is secured to the bracket substantially as shown and for the purposes described.

4. In a tiltable bed, brackets projecting

from a wall or panel, said bed including a bed frame pivotally mounted in said brackets, means for counter-balancing said bed, said means comprising springs extending lengthwise within the bed frame and secured to the end of the bed frame further from the pivotal support, a flexible connection from the free end of the spring through the head of the bed and secured to the bracket adjacent to the position of the head of the bed frame when the same is in an up-ended position against the wall, but at a distance from the wall less than the distance from the wall to the pivotal axis of the bed, means at the head of the bed for coöperating with said flexible connections to engage the same at a point further from the wall than the point at which the flexible connection is secured to the bracket, a plate secured to each side member of the bed frame toward the end opposite its pivotal support, said plates having brackets to support the under-side of the side frames, and a foot member and legs pivotally mounted on the side plates, substantially as shown and described.

5. In a tiltable bed, a bed frame, brackets on which said bed frame is pivotally mounted, said brackets being adapted to be secured to a wall or panel, means for counter-balancing said bed, said means comprising springs secured to the bed frame, and flexible connections from the springs through the head end of the bed and fastened to the supporting bracket, at a point that is passed by the point where the connection passes through the head of the bed frame whereby an initial tendency is given the upper end of the bed from the panel or wall to facilitate the lowering and conversely to oppose a check at the upper limit of the bed's position, substantially as shown and for the purposes described.

In testimony whereof I have signed my name to this specification in the presence of two subscribing witnesses.

NATHAN C. MERRILL.
